UNITED STATES PATENT OFFICE.

JOHN G. MILLER, OF CHICAGO, ILLINOIS, ASSIGNOR TO THE BAKER MANUFACTURING COMPANY, OF CHICAGO, ILLINOIS, A CORPORATION OF ILLINOIS.

ROAD-GRADING MACHINE.

1,114,173.

Specification of Letters Patent.

Patented Oct. 20, 1914.

Application filed December 15, 1911. Serial No. 666,007.

To all whom it may concern:

Be it known that I, JOHN G. MILLER, a citizen of the United States of America, and a resident of Chicago, county of Cook, State of Illinois, have invented certain new and useful Improvements in Road-Grading Machines, of which the following is a specification.

The main objects of this invention are to provide an improved construction for road grading machines; to provide an improved mounting of the scraper on the supporting structure; to provide improved means for maintaining the angularity of the scraper with respect to the direction of travel; to provide improved means for controlling the vertical adjustment of the scraper; and to provide improved means for effecting the sidewise shifting of the rear wheels with respect to the direction of travel of the scraper.

An illustrative embodiment of this invention as applied to a road scraping and grading machine is shown in the accompanying drawings, in which:—

Figure 1 is a perspective view. Fig. 2 is an enlarged fragmentary sectional detail. Fig. 3 is a plan view of the rear portion of the machine.

In the form shown in the drawings, the machine comprises a supporting structure carried by a pair of trucks located at the forward and rear ends thereof, and a scraper controlled by lever mechanism mounted on the supporting structure. The supporting structure comprises a pair of frames 1 and 2, carried by the rear truck 3 and forward truck 4, and pivotally connected together at 5 intermediate of said trucks. The frame 1 is of bent bar construction, and comprises the main member 6 supported by braces 7 and 8 above the platform 9, and on which the operating mechanism is mounted, as will hereinafter appear. The frame 2 is preferably a draft beam or a reach, having its outer end connected to the truck 4 by means of a rod or pintle 10, rotatably mounted in plates secured to the end of the reach. The rod 10 is rigidly held at its lower end between the clamp plates 11 by means of the bolt or pin 12, and the clamp plates 11 are pivotally connected at 13 to the axle 14 of the front truck 4 to allow a transverse racking of the truck in a vertical plane with respect to the supporting structure. The tongue or draft

appliance 15 is connected to the rod 10 by means of a plate 16 secured to the horizontal arm 17 of the rod 10. The plate 16 is offset so that the center line of the tongue 15 is in alignment with the center line of the reach 2, for obvious reasons.

A scraper 18 of the usual curved shape is suspended beneath the supporting structure by a pintle 19, having a pad or plate 20, riveted to the scraper. The pintle 19 is journaled on a plate 19.1 secured to the reach 2, rearward of the pivotal connection 5 of the two frames in such a manner as will allow the scraper to be swung in a horizontal plane to different angular positions with respect to the direction of travel, and also in a vertical plane for the purpose of altering the depth of the cut made by its extremities. A semi-circular, segmental member 21, preferably of angle iron, has its ends bent downwardly and riveted to the back of the scraper 18. A clip or keeper 22 is secured to the under side of the rear portion of the reach 2, and is adapted to embrace the segmental member 21 and coact therewith in supporting the scraper. A pin 23, extending downwardly through the reach 2, is adapted to be received in apertures 24 in the segmental member 21, for adjusting and maintaining the angularity of the scraper with respect to the direction of travel.

In order to avoid excessive strains and assist in positively maintaining the angularity of the scraper 18 with respect to the direction of travel, a guy connection 25 is employed for connecting the forward end of the scraper to the reach 2. The guy connection comprises a pair of rods connected together by a turn buckle 26, one of the rods having its end inserted into the aperture 27 of one of the plates or lugs 28 riveted to opposite ends of the scraper 18, and secured by a nut 29. The other rod of the guy connection has a chain 30 connected thereto, the links of which are adapted to engage one of the hooks 31, of which there is one on each side of the reach 2. The chains allow the guy to be adjusted to suit the angular position of the scraper.

The adjustment of the scraper for regulating the lateral slope of the cut is controlled by means of levers 32, of which there is one at either side of the frame 1. These levers are pivoted at 33 to an arm, which also has formed thereon a notched segment

with which the usual locking mechanism on the lever coacts for locating the position of the lever. A link 34 is connected to the forward ends of each of the levers 32, and has its lower end rounded and pointed as at 35, so as to be insertible into one of the series of apertures 24 in the segmental member 21. A hook 36 is pivoted to each of the links 34 above the part 35, and is adapted to be 10 swung up out of the way of the part 35 when it is being inserted into one of the apertures 24, and then swung down below the segmental member 21, as is shown at the right of Fig. 1. A locking ring 37 is arranged to embrace the link 34 and the hook 36 for securing them against accidental disengagement from the segmental member 21.

The mechanism for obtaining a relative 20 shifting of the frames 1 and 2, for raising and lowering the scraper 18, comprises a lever 38 secured to the end of a shaft 39 supported in a bearing 40 on the cross bar 41. The shaft 39 has a transversely disposed 25 arm 42, bifurcated at its forward end, so as to receive a link 43, the lower end of which is secured between the ears 44 of a plate attached to the reach 2. A notched segment 45 is arranged to coact with the usual locking 30 detent on the lever for locking the latter in different angular positions. A spring 46 is connected at one end to the link 43 and at its other end to a hook 47 secured to the cross-bar 41, and normally urges the rearward 35 end of the reach 2 in the upward direction so as to counter-balance the weight of the scraper.

The supporting structure is provided with 40 rectangular members 48 suitably secured to the braces 8 and the platform 9, and adapted to have sliding engagement with the axle 49 of the rear truck 3. A rack 50 is secured to the axle 49, and meshes with a pinion 51, which is secured to the end of 45 the shaft 52, journaled in a bearing 53 and carrying at its upper end a hand wheel 54. Rotation of the hand wheel causes the pinion 51 to shift the supporting structure along the axle 49. A seat 55 is secured to 50 the upper end of a brace 56, which is slidably mounted in a recess 57 on the platform 7, being secured in any position of adjustment by means of the bolt 58. The wheels 55 of the rear truck are provided with the usual annular flanges 59, to prevent transverse shifting of the truck when the scraper 18 is in operation.

The operation of the device shown is as follows:—The scraper 18 may be set to a desired angle with respect to the direction of travel, by withdrawing the pin 23 and swinging the scraper on the pintle 19. After the scraper is set, it may be locked in

position by inserting the pin 23 into one of the apertures 24. The guy connection 25 65 is then attached to the lug 23 on the forward end of the scraper, and to the respective hook 31, so as to positively maintain the angularity of the scraper 18 with respect to the direction of travel and relieve the 70 other connections from excessive strain. The lever 32, at the side of the machine opposite that on which the guy connection is arranged, is connected to the segmental member 21 by means of the part 35 and 75 hook 36, as hereinbefore explained. The manipulation of said lever determines the lateral slope of the scraper. By operating the lever 38, the frames 1 and 2 may be given a relative movement so as to regulate the elevation of the scraper 18 with respect to the wheel base of the machine. The scraper 18 may also be shifted bodily in a horizontal direction by turning the hand wheel 54, which will cause the pinion 51 85 and rack 50 to shift the supporting structure along the axle 49. The machine follows the direction of the pull on the draft appliance 15, since the turning of the rod 10 turns the front truck. The pivotal connection of the axle 14 of the truck to the clamp plates 11 permits the front truck to tilt laterally with respect to the frame structure when traveling over uneven ground, without interfering with the operation of 90 the scraper.

Although but one specific embodiment of this invention is herein shown and described, it will be understood that numerous details of the construction shown may be 100 altered or omitted without departing from the spirit of this invention, as defined by the following claim.

I claim:—

In a road grading machine, the combination 105 of a supporting structure, a scraper suspended from said structure and shiftable in a horizontal plane, a segmental member carried by said scraper, means on said structure adapted to coact with said segmental member for adjusting the angular position 110 of said scraper with respect to the direction of travel, levers located at opposite sides of said structure, and links attached to said lever and adapted to be separately connected 115 to said segmental member at points directly below the corresponding levers whereby said scraper is adapted to be tilted in a vertical plane by the independent operation of one or the other of said levers.

Signed at Chicago this 13th day of Dec. 120
1911.

JOHN G. MILLER.
